PORTABLE COOKER

Joe A. Lemmons, 302 Corrigan, Fred A. Lemmons, 1601 Phillips, and Floyd J. Page, 302 Corrigan, all of Brownwood, Tex. 76801
Filed Jan. 20, 1966, Ser. No. 521,875
8 Claims. (Cl. 126—137)

ABSTRACT OF THE DISCLOSURE

The portable knockdown cooker shown is expressly, but not necessarily, designed and adapted for on-the-spot use in an indoors fireplace. The required fire can be built in the fireplace or, alternatively, in an accompanying pan for charcoal broiling. In both forms of the invention the horizontal grille is adjustable to the level desired on vertical support legs. These legs can be self-standing (FIG. 7) or detachably suspended from hanger hooks bracketed to a fixed fireplace lintel (FIG. 3). The device can be used for camping, backyard cookouts and set up or dismantled in minutes. It is compact, convenient, and totally collapsible for storing and transporting. It is light in weight but sturdy for heavy utensils and can be used, without fire, as a flower support and display rack in the fireplace or elsewhere.

The present invention relates to portable as well as knockdown cookers and has reference to a structure which is adapted to be used, generally speaking, within the wall-enclosed confines of a fireplace, a barbecue pit, or the like whenever one desires to use the device indoors or outdoors, as the case may be.

Two embodiments or forms of the inventive concept are disclosed in the views of the drawings and will be hereinafter generically and specifically set forth and defined.

Generically construed the structure has to do with a multipurpose adaptation, that is, one which not only lends itself to practical and feasible use in a room fireplace but, in addition to its use for grilling and barbecuing foods indoors, can be used as a fireplace rack in that it provides a feasible shelf on which the user can place potted plants and flowers if so desired.

Briefly, the broad aspect of the invention is characterized by a screened or grille-equipped frame which constitutes and provides a grate (alternatively a shelf or rack) which is capable of use within the confines of the walls of the fireplace and is capable of supporting a fry pan, cooking utensils or the like and is also usable as a food cooking grille. The support means for the frame is characterized by a pair of correspondingly constructed legs having means whereby the legs are capable of being vertically supported or suspended in spaced parallel relationship in an accessible front part of the fireplace. The front or outwardly disposed frame member of the frame is such that it bridges the support legs and has outstanding accessible handgrips. It is further provided with suitably constructed and arranged adapter brackets which are slidably and removably mounted on their respectively cooperable legs in a manner to support the frame in a plane at right angles to the spaced parallel but common plane of the supported legs, this in a manner that the frame itself projects into the enclosed space in the fireplace.

More specifically, novelty is predicated on one form or embodiment wherein the legs are T-shaped, have slotted upper ends capable of being engaged with hooks, said hooks being carried by attaching brackets and said brackets being securely attachable to and hung from a lintel which is positively anchored in the upper forward

2

portion of the fireplace. The legs in this situation accommodate brackets on the frame and the frame provides the aforementioned grille or rack. The brackets have setscrews and the setscrews engage the suspended legs whereby to thus provide a simple, practical and acceptable indoors "cookout" structure.

The other embodiment of the invention is characterized, as will be later appreciated, by a pair of L-shaped leg units whose vertical portions accommodate brackets carried by the screened or grille-equipped frame, the frame members being provided with means such as cleats or the like to accommodate chains. These chains are connected to corner portions of a tray or pan and are also connectible with the cleats. The pan can be used either as a drip pan or as a tray for charcoal if one desires to build the fire in the receptacle portion of the tray or pan directly beneath the grille or screen.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a view in section and elevation with the invention in elevation and the view being taken on the plane of the irregular section line 1—1 of FIGURE 3;

FIGURE 2 is a front view or elevation showing the fireplace, for example, an indoor fireplace with the insertable and removable as well as adjustable cooking device mounted for use therein, observing the structure of FIGURE 3 in a direction from right to left;

FIGURE 3 is a section taken on the plane of the line 3—3 of FIGURE 1;

FIGURE 4 is a detail horizontal section on an enlarged scale on the section line 4—4 of FIGURE 3;

FIGURE 5 is an enlarged fragmentary view which shows most of the particulars and which is taken on the plane of the section line 5—5 of FIGURE 1;

FIGURE 6 is a fragmentary horizontal section on the line 6—6 of FIGURE 5; and

FIGURE 7 is a view in perspective of the bodily insertable and removable knockdown cooking device, that is a modified form of the same.

Referring to FIGS. 1 to 6, inclusive, the brick or equivalent built-in fireplace (which may be construed as either indoors or outdoors) is denoted by the numeral 10, the horizontal bottom being denoted at 12 and the open front or hearth portion being denoted generally at 14. The chimney is denoted at 16 in FIG. 3. As usual the upper frontal portion of the fireplace is provided with a reinforcing metal bar or lintel 18. In carrying out the principles of the invention the lintel 18 (see FIG. 5) serves to accommodate attaching and anchoring fixtures, a pair of such fixtures being used and each fixture is of elongated U-shaped form as denoted at 20 and has an upstanding pronged outer end 22 which is embedded around the edge of the forward portion of the lintel in the manner shown. The opposite lateral inward end portion 24 is provided with a setscrew or equivalent clamping means 26 which is clamped against the inner edge of the lintel. Accordingly, the fixture 20 is securely attached to the lintel and each fixture is provided with a suitably positioned adapter bracket which is of L-shaped form as denoted generally at 28. The vertical leg of the adapter bracket denoted at 30 is provided on its inward side with a pair of opposed parallel hanger hooks 32. These bracket-equipped fixtures are installed and of course left in place to accommodate the insertable and removable knockdown cooking device. This device as more completely shown in FIGS. 1 to 4 comprises a grate unit, more specifically a generally rectangular frame 34 char-

acterized by a rearward or inward frame member 36 which is channel-shaped in form and integrally connected with a pair of side frame members 38 and a forward or front frame members 40 (see FIG. 4). These frame members support the rigid openwork screen or grating which constitutes the part described as the grille 42.

The forward frame members 40 is provided with means whereby it may be adjustably and detachably joined with support means. The support means here comprises a pair of duplicate substantially T-shaped suspending legs 44 (see FIG. 5) whose upper end portions 46 are provided with suitably arranged and paired slots 48 which constitute keepers and are releasably connected with the hanger hooks 32. For best results the forward member of the frame is provided with attaching brackets, there being two such brackets and each being the same in construction. Each bracket is denoted by the numeral 48 and is of general U-shaped form and comprises an upper arm 50 and an opposed spaced parallel lower arm 52, these arms having their end portions 54 straddling and connected with the adjacent frame member 40. The web portion 56 is provided with a screw-threaded hole to accommodate the shank 58 of a setscrew 60. This bracket and setscrew arrangement permits the brackets to be slidily and adjustably mounted on the support or suspension legs 44. To accommodate the legs each of the arms of each bracket has a T-shaped slot 62 therein as shown in FIG. 6. It follows that the T-slotted brackets are slidily and detachably and adjustably mounted on the legs 44 and the legs are hung from the hanger hooks 32 carried by the adapter brackets 20 on the fixtures 20.

The device as shown and described in detail in primarily designed and adapted to serve as an on-the-spot indoor fireplace "cookout" grille. The parts are such that they fit well together and permit ready erection and dismantling. A consideration of the structure appearing in FIGS. 1 to 3 in particular will show the structure and how it is assembled for use. When the device is not being used for indoor cooking purposes it can be employed as a rack or shelf. This is to say, the grate or grille now becomes a handy shelf and one can support potted plants and flowers thereon within the limits of the fireplace to add to the desired alcove effect if so desired.

The form of the invention shown in FIG. 7 is substantially the same as that already described but will be touched upon separately. Here the grate or grating comprises a rectangular frame 64 having a forward frame member 66, rearward or inward frame member 68 and side frame 70, said frame members supporting a suitably constructed and attached grille or grating 72. In both forms of the invention the forward frame member is provided with spaced apart handgrips 74. The handgrips in this arrangement are spaced inwardly of the U-shaped end brackets 76. Here again the brackets have upper and lower arms 78 with T-shaped slots to accommodate the T-shaped support legs or uprights 80. The desired connection is achieved by providing the web portions 82 with setscrews 84. The leg means here is L-shaped in side elevation and includes in each unit not only the vertical member 80 but the horizontal member 86 which resides on the floor of the pit or fireplace in an obvious manner. For convenience these L-shaped units are referred to broadly at 88. The numeral 90 designates an open-top tray or pan which can be used as a grease pan or, alternatively, as a tray for charcoal briquets or the like used in building a fire directly beneath the grille. The left and right walls of the tray have corner attached chains 92 which are connected with keeper slots 94 provided therefor in oppositely disclosed cleats 96 mounted on the side frame members 70. It will be obvious that this form of the invention is possessed of the general structural characteristics and purposes of the form shown in FIGS. 1 to 6 inclusive. It is believed that the construction of the parts, the manner in which they are assembled and used in both

forms of the invention will be clear after having read the description of the details in conjunction with the views of the drawing. Accordingly, a more extended description is believed to be unnecessary.

5 The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A portable cooker of the class described comprising a pair of substantially duplicate L-shaped members 15 constituting companion support units, each unit embodying a horizontal leg and a vertical leg, said legs being substantially T-shaped in cross-section, said units being adapted to assume spaced apart parallel relationship when in use, a frame disposed at right angles to the vertical legs and having an openwork grille attached thereto, said frame having a front frame member provided with outstanding handles and also provided outwardly of the handles with a pair of substantially U-shaped brackets, 20 said brackets having arms straddling and affixed to the front frame member and said arms having T-shaped slots slidily receiving said vertical legs, said brackets being further provided with setscrews engageable with said vertical legs and serving to detachably and adjustably mount the frame on said vertical leg.

2. The structure defined in claim 1 and in combination, a pan having an open top, said pan being of a size corresponding to and underlying said frame in spaced relationship, said pan being provided on end walls thereof 35 with attaching and adjusting chains, the side members of said frame being provided with outstanding cleats, said cleats having notches and said notches providing keeper slots, and free end portions of said chains being releasably engageable with said keeper slots so as to 40 detachably and adjustably mount the pan beneath the frame.

3. For use within the confines of a fireplace barbecue pit or the like either indoors or outdoors, a multi-purpose structure embodying a rigid grille-equipped frame capable of supporting a fry pan, cooking utensils or the like 45 and, alternatively, usable as a food cooking grille, a pair of like legs having means whereby said legs may be vertically supported in spaced parallel relationship in an accessible front part of said fireplace, said frame having an outwardly positionable frame member provided with outstanding easily accessible and usable handgrips, said frame member being further provided at the respective outer ends thereof with adapter brackets slidily and removably mounted on their respectively operable legs and supporting said frame in a plane at 50 right angles to the horizontal plane of said legs with the entire frame adapted to project into the fire isolating space of said fireplace, said handgrips being arranged in spaced parallel relationship inwardly of their respectively adjacent brackets, said legs being T-shaped in cross-section and said brackets having corresponding T-shaped slots conformingly and slidily receiving their respectively cooperable legs.

4. The structure defined in claim 3, and wherein each bracket is U-shaped and embodies upper and lower arms having inward ends straddling and affixed to a coacting portion of said outwardly disposed frame member, having their outer ends joined by a web, said web being equipped with a setscrew projecting into the space between the arms, said T-shaped slots being paired and aligned and 65 coordinating in permitting said T-shaped legs to be slidily keyed therein.

5. The structure defined in and according to claim 3 and wherein the side members of said frame have fixed cleats with projecting ends bifurcated and defining keeper notches, a pan underlying said grille-equipped frame in 70

spaced parallel relation and disposed in a plane at right angles to said legs, and chains carried by and supporting said pan, said chains being detachably and adjustably supported by said cleats.

6. The structure defined in and according to claim 3 and wherein the means supporting said legs in vertical spaced parallel relationship at the front part of said fireplace comprises a relatively stationary horizontal lintel, a pair of attaching and anchoring fixtures detachably and adjustably mounted on and supported from longitudinally spaced portions of said lintel, each fixture provided with a companion adapter bracket, each bracket being provided with hanger hooks, the upper end portion of said legs being apertured and said apertured end portion being attached to and hung from their respectively cooperable hanger hooks.

7. For use within the wall enclosed confines of a fireplace, barbecue pit or the like either indoors or outdoors, a multipurpose structure embodying a rigid grille-equipped frame capable of supporting a fry pan, cooking utensils or the like and, alternatively, usable as a food cooking grille, a pair of like legs having means whereby said legs may be vertically supported in spaced parallel relationship in an accessible front part of said fireplace, said frame having an outwardly positionable frame member provided with outstanding easily accessible and usable handgrips, said frame member being further provided at the respective outer ends thereof with adapter brackets slidably and removably mounted on their respectively cooperable legs and supporting said frame in a plane at right angles to the horizontal plane of said legs with the entire frame adapted to project into the fire isolating space of said fireplace, said legs being L-shaped in side elevation and having vertical and horizontal component portions, said horizontal component portions constituting feet adapted to reside flatwise on the floor of the fireplace for support, said handgrips being disposed in spaced apart parallel relationship inwardly of their respectively adjacent brackets, said legs being T-shaped in cross-section and said brackets having corresponding T-shaped slots conformingly and slidably receiving their respectively cooperable legs, each adapter bracket being U-shaped and embodying upper and lower arms having inward ends straddling and affixed to a coacting portion of said outwardly disposed frame member, having

their outer ends joined by a web, said web being equipped with a setscrew projecting into the space between the arms, said T-shaped slots being paired and aligned and coordinating in permitting said T-shaped legs to be slidably keyed therein, the side members of said frame having fixed cleats with projecting ends bifurcated and defining keeper notches, a pan underlying said grille-equipped frame in spaced parallel relation and disposed in a plane at right angles to said legs, and chains carried by and supporting said pan, said chains being detachably and adjustably supported by said cleats.

8. A portable cooker comprising a pair of companion support units each unit embodying a vertical leg, said vertical legs being disposed in spaced apart parallel relationship, a frame disposed at right angles to said vertical legs, said frame provided with a complemental open-work grille, said frame having a front member provided with brackets, said brackets being slidably and adjustably mounted on their respectively cooperable vertical legs, a pan having an open top, said pan being of a size corresponding to and underlying said frame in downwardly spaced generally parallel relationship, said pan being provided with end walls having pan attaching and adjusting chains thereon, the side members of said frame being provided with outstanding chain attaching cleats, said cleats having notches, and said notches providing keeper slots for said chains, and said chains having free end portions releasably and adjustably engageable with their respectively cooperable keeper slots in a manner to detachably and adjustably suspend the pan in cooperative relationship beneath said frame.
